UNITED STATES PATENT OFFICE.

CHARLES W. WOLFF, OF SHIRLEY, MASSACHUSETTS, ASSIGNOR TO THE
C. A. EDGARTON MANUFACTURING COMPANY, OF SAME PLACE.

SUSPENDERS.

SPECIFICATION forming part of Letters Patent No. 592,620, dated October 26, 1897.

Application filed June 11, 1897. Serial No. 640,319. (No model.)

To all whom it may concern:

Be it known that I, CHARLES W. WOLFF, of Shirley, in the county of Middlesex and State of Massachusetts, have invented certain new and useful Improvements in Suspenders, of which the following is a specification.

This invention relates to suspenders intended to be worn by men engaged in severe manual labor, and particularly to suspenders composed of two strips which are provided at their ends with means for connection to the trousers and are crossed at the back of the wearer, there being a loose connection between the strips at their point of intersection, so that each has a limited independent endwise movement.

The invention has for its object to provide a more substantial and durable means for adjustably and loosely connecting the strips at their point of intersection than heretofore.

The invention consists in the improvements which I will now proceed to describe and claim.

Of the accompanying drawings, forming a part of this specification, Figure 1 represents a side view of the rear portions of the two strips and connecting means attached thereto embodying my invention. Figs. 2 and 3 represent the pieces which constitute the connection between the two crossed strips.

The same letters of reference indicate the same parts in all the figures.

In the drawings, *a* and *a'* represent two strips of webbing or other suitable material adapted to be attached at their ends to the waistband of a pair of trousers and to extend over the shoulders of the wearer. I do not here show the entire length of the strips, only the rear portions, which are attached to the back of the waistband and intersect each other, being shown. There is no direct connection between the strips *a a'* at their point of intersection, each being free to move endwise independently.

To the strip *a* are attached two strands *b b*, which extend lengthwise of the strip and are attached thereto at their ends only, the intermediate portions of said strands being free from the strip *a* and constituting elongated loops. The strands *b b* are preferably made from one piece of leather or other suit-

able material by cutting a slit *b²* from one end of said piece partly to the other end, as shown in Fig. 3, the two strands being therefore integral with each other. The ends of the strands are attached to the strip *a* by means of stitches *s*.

b' b' represent two similar strands extending lengthwise of the strip *a'* and attached thereto at their ends by stitches *s'*, the intermediate portions of the strands *b' b'* being free from the strip *a'*. The strand *s s'* are preferably made integral with each other by cutting a slit *b³* in a continuous piece of leather, as shown in Fig. 2, the slit terminating within the ends of the piece, so that both ends of the strands are integrally connected.

In assembling the described parts the strands *b' b'* are first attached to the strip *a'*, and then the strip *a* is passed between the strip *a'* and the strands *b b*, and the strands *b b*, which have been previously attached at their connected ends to the strip *a*, are interwoven with the strands *b' b'*, as shown in Fig. 1, and then attached at their free ends to the strip *a*.

The two pairs of strands, connected, as described, to each other and to the springs *a a'* and interwoven along their free portions, constitute a connecting device which permits each strip to have a limited independent longitudinal movement without any considerable lateral or edgewise play, the combined width of each pair of strands substantially filling the space between the two series of stitches that connect the ends of the other strands to their strip, so that there is but little independent edgewise movement of either strip. The integrally-connected ends of the strands stitched to the suspender-strips make the construction strong and durable, and the subdivision of the two attached pieces into interwoven strands enables said pieces to be made wider and therefore to give greater strength to the construction than would be possible if the suspender-strips *a a'* were connected by two crossing pieces, one attached to each strip.

It will be observed that the lines of stitches *s s* which unite the pair of strands *b b* to the strip *a* are substantially parallel with the edges of the strip *a'* and strands *b' b'*, and that the lines of stitches *s' s'* which unite the pair of strands *b' b'* to the strip *a'* are sub-

stantially parallel with the edges of the strip *a* and strands *bb*. Therefore when one of the suspender-strips moves endwise across the other its limit of movement is determined by 5 a line of stitches which oppose further movement by an obstruction which extends for some distance along the edge of the part which abuts against said line. It will be readily understood that if the line of stitches extended 10 across each strip at a right angle thereto, or nearly so, there would be but one or two stitches to oppose the movement described and receive the wear of the abutting edge and said one or two stitches would soon wear out 15 and break.

I claim—

1. Suspenders comprising two crossed strips free from direct connection with each other, a pair of strands attached at their ends to one 20 strip, and a pair of strands attached at their ends to the other strip and interwoven with the first-mentioned pair, the line of the attaching means which unite each pair of strands to their strip being substantially par-

allel with the edges of the other pair of strands 25 and strip, substantially as and for the purpose set forth.

2. Suspenders comprising two crossed strips free from direct connection with each other, and two crossed connecting-pieces each subdivided into a plurality of strands, the said pieces being attached at their ends to the strips and unattached and interwoven between their ends, the line of the attaching means which unite each connecting-piece to 30 its strip being substantially parallel with the edges of the other connecting-piece and its strip, substantially as and for the purpose set forth.

In testimony whereof I have signed my 40 name to this specification, in the presence of two subscribing witnesses, this 1st day of June, A. D. 1897.

CHARLES W. WOLFF.
